RACK AND GEAR ACTUATED CLAMP

Arnold Simonsen, San Francisco, Calif.

Application May 17, 1948, Serial No. 27,478

2 Claims. (Cl. 144—303)

1

The present invention relates to new and useful improvements in clamps and more particularly to a C type clamp including a stationary and a movable jaw coacting therewith.

An important object of the invention is to provide rack and gear operating means for moving the movable jaw into and out of its clamping position and to further provide releasable operating means for the gear or pinion to permit a quick adjustment of the clamp.

A further object of the invention is to provide a worm gear operating means for the pinion whereby to hold the movable jaw in its adjusted position.

A still further object of the invention is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figures 2 and 3 are transverse sectional views taken respectively on the lines 2—2 and 3—3 of Figure 1;

Figure 4 is a longitudinal sectional view showing the pivoted form in pinion operating position;

Figure 5 is a fragmentary longitudinal sectional view showing the worm in disengaged position;

Figure 6 is a top plan view, and;

Figure 7 is an enlarged perspective view of the locking means for the worm.

Referring now to the drawings in detail wherein for the purpose of illustration I have disclosed a preferred embodiment of the invention the numeral 5 designates a substantially channel shaped guide having a stationary jaw 6 suitably secured in the upper portion and at one end of the guide. A J-shaped movable jaw 7 includes a jaw face 8 at its curved end coacting with the stationary jaw 6 and a shank portion 9 slidable in the lower portion of guide 5.

A rack 10 is secured in a longitudinal position on the upper edge of shank 9 to a distance of approximately one half the width of the shank, the remaining upper surface of the shank 9 forming a track 11 with which a rear stationary guide block 12 is engaged together with a front roller 13 journaled in the guide 5 on a transverse

pin 14 for traveling on the track 11 and to hold the shank against play in the guide 5 during its sliding movement.

A pinion gear 15 is formed at one side with a worm gear 16 and journaled on a pin 17 transversely of the guide 5, the pinion being engaged with the rack 10. A worm 18 is provided with a shaft 19 which is journaled at its front end in a bearing collar 20 which is pivoted to the under side of stationary jaw 6 by a suitable type of hinge structure 21. The rear end of the shaft projects rearwardly of the guide 5 and is formed with a manipulating knob 22.

The worm 18 is swingable vertically into and out of engagement with the worm gear 16, the rear end of the shaft being engaged by a coil spring 23 seated on the guide block 12 to raise the worm 18 out of engagement with the worm gear 16 and the worm is locked in its engaged position by a bearing 24 constructed substantially in the form of a yoke which straddles the rear end of shaft 19 and is pivoted on a transverse pin 25 journaled in the guide 5. One end of shaft 25 is provided with a lever 26 positioned outwardly at the side of the guide 5 and operated by a raising and lowering movement to swing the bearing 24 into and out of engagement with the shaft 19.

In the operation of the device the shank 9 of movable jaw 8 is slidable in the lower portion of guide or housing 5 as indicated for movement toward and away from jaw 6.

By swinging lever 26 downwardly, bearing 24 is engaged with shaft 19 to swing worm 18 downwardly into its engaged position with worm gear 16 and the turning of knob 22 will operate the gears and rack and pinion to slide shank 9 inwardly in a direction to close jaw 8. The worm 18 is constructed to operate in a direction to slide rack 10 and shank 9 rearwardly in a closing action of jaw 8 and the worm holds the shank and movable jaw in its closed position.

By raising lever 26 the bearing 24 is released from shaft 19 and spring 23 raises worm 18 to disengage worm gear 16 and the movable jaw 8 and shank 9 are free to slide in housing 5 to open the jaw or to provide a quick closing adjustment thereof. The jaws 6 and 8 may be constructed of metal or wood.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A clamp comprising a channel guide, a movable jaw including a rack slidable in the guide, a fixed jaw secured to the guide, a gear in said guide between said rack and fixed jaw for operating said rack, a drive for said gear comprising a driving worm in said guide between said gear and fixed jaw rotatably and pivotally attached to the fixed jaw for swinging into and out of driving position, a worm shaft extending from said worm out of said guide for manipulation to swing and rotate said worm, a guide block for said rack fixed in said guide in sliding engagement with said rack, and a spring seated in the block and engaging said shaft to normally swing said worm out of driving position.

2. A clamp according to claim 1 wherein a lever

equipped pivoted bearing for said shaft is provided in said guide for swinging against said shaft to swing said worm into driving position in opposition to said spring and to maintain said worm and gear in engagement.

ARNOLD SIMONSEN.
